DUPLICATING APPARATUS

Alfred Marchev, La Grange, Ill., assignor to Dit-
to Incorporated, Chicago, Ill., a corporation of
West Virginia

Application September 20, 1937, Serial No. 164,750

5 Claims. (Cl. 101—132)

The present invention relates to duplicating machines and is particularly applicable to that type of duplicating machine wherein a master copy is made in reverse with suitable copying ink, and copy sheets have the record transferred thereto by moistening the copying sheets with a suitable solvent and pressing them into engagement with the master sheet. In machines of this character, it is common practice to secure the 10 master sheet to a platen in the form of a rotatable drum and to supply the copy sheets to the drum by passing them between combined feeding and moistening rolls, one roll being supplied with a suitable solvent which it transfers to the surface of the copy sheet.

Machines have been used heretofore wherein means are provided for rotating the drum from a suitable drive member which is so connected to the drum that, upon each complete rotation of 20 the drum, the drum is stopped in the proper position for the advancement of a fresh copy sheet thereto, in which machines the driving means continues to operate while the drum remains stationary so as to provide a dwell or stop 25 period for the drum during which the operator may engage a fresh copy sheet with the combined feeding and moistening rolls. The present invention provides in a machine of this general type a novel means whereby a fresh copy sheet is 30 automatically advanced during this dwell period from a stack of sheets upon a copy sheet tray. The sheet feeding means in my improved machine advances the copy sheet to the combined feeding and moistening rolls while such rolls 35 are held stationary so as to serve as stop means for limiting the forward movement of the sheet and holds it there until the drum and the rolls have started a new duplicating cycle.

The features and advantages of the invention 40 will appear more fully as the description proceeds, reference being had to the accompanying drawings wherein a preferred embodiment of the invention is shown.

45 In the drawings—

Fig. 1 is a longitudinal sectional view through a machine embodying the invention, the sectional view taken substantially on the line 1—1 of Fig. 3;

50 Fig. 2 is a sectional view like Fig. 1, but showing the parts in a changed position;

Fig. 3 is a plan sectional view taken substantially on the line 3—3 of Fig. 1;

55 Fig. 4 is a plan sectional view taken substantially on the line 4—4 of Fig. 1;

Fig. 5 is a sectional view taken on the line 5—5 of Fig. 1;

Fig. 6 is an enlarged sectional view taken on the line 6—6 of Fig. 3;

Fig. 7 is a fragmentary sectional view taken on the line 7—7 of Fig. 3;

Fig. 8 is an enlarged fragmentary plan view of a portion of the sheet feeding mechanism; and

Fig. 9 is a sectional view taken on the line 9—9 10 of Fig. 7.

Referring now to the drawings, the invention is shown as embodied in a duplicating machine which comprises a framework composed of a pair of sheet metal side frames 10 and 11 having supporting feet 12 and 13 thereon, a back end frame 14 connecting the side frames 10 and 11 and a front end frame 15 connecting the side frames 10 and 11. The side frames 10 and 11 are provided with flanges 16 and 17 extending inwardly 15 toward each other, and the end frames 14 and 15 overlap with and are secured to these flanges to provide a rigid structure. The side frame 10 carries a mounting plate 18, and the side frame 11 carries a mounting plate 19. The plates 18 20 and 19 have inwardly extending tubular portions 20 and 21 formed thereon to provide support for a pair of bushings 22 and 23 in which a drum shaft 24 is journaled. End plates 25 and 26 are secured to the opposite ends of the shaft 24 by 30 screws 27 and 28 so as to prevent endwise movement of the shaft 24.

The shaft 24 has a duplicating drum 29 keyed thereto by a pin 30 which is screw threaded into a hub portion 31 provided on one end of the drum 35 29. The shaft 24 also has keyed thereto a gear 32 and a gear 33.

Below the drum 29, a pair of studs 34 and 35 (see Fig. 5) are fixed in the side frames 10 and 11 and carry inwardly extending screw threaded pins 40 36 and 37. The pins 36 and 37 terminate in reduced end portions 38 and 39 which support the inner end of a receiving tray 40. The receiving tray 40 has side flanges 41 and 42 provided with notches in which the portions 38 and 45 39 engage. The rear end frame 14 has a bracket 43 thereon for supporting the tray 40. The pins 36 and 37 also support a pair of swinging arms 44 and 45 which are pivoted on the pins 36 and 37 and held in place by a pair of nuts 46 and 47. 50 The swinging arms 44 and 45 are formed as shown best in Figs. 1, 2, and 3 with forwardly extending portions 48 and 49. The portions 48 and 49 support a pair of ball bearings 50 and 51 which rotatably mount a shaft 52 of a platen roller 53. 55

The platen roller 53 is pressed upwardly against the drum 29 with the desired amount of pressure by adjusting the arms 44 and 45 at their lower ends. The arm 44 at its lower end carries an adjusting stop screw 54, and the arm 45 carries a similar adjusting stop screw 55. The stop screws 54 and 55 have their heads engaging flat sided enlargements 56 and 57 which are provided on a pair of sleeves 58 and 59 keyed to a shaft 60 that is journaled in the side frames 10 and 11. The shaft 60 has a knurled finger piece 61 at one end thereof on the outside of the side frame 11 so that it can be turned to move the heads of the screws 54 and 55 from the flat surfaces of the enlargements 56 and 57 onto the rounded portions thereof which results in increasing the pressure of the platen roller 53 against the drum 29.

The duplicating drum 29 has a gripper shaft 62 journaled in suitable plates 63, one of which is shown in Fig. 6, to support master sheet grippers 64 which are of the general construction shown in my prior application Serial No. 82,402, filed May 29, 1936, for Duplicating apparatus. The shaft 62 has an operating lever 65 fixed thereto which is normally held by a spring 66 in position to close the gripper 64. One end of the spring 66 is secured to the lever 65, and the other end is secured to a pin 67 mounted on the end of the drum 29. For opening the gripper 64 to release an old master sheet and to insert a new one, a lever 68 is pivoted on a pin 69 carried by the side frame 11. This lever is adapted to be pressed against the free end of the lever 65 by a hand lever 70 to open the grippers in the manner described in my application hereinbefore mentioned. The lever 68 carries a stop pin 71 that is adapted to engage in an aperture 72 formed on the surface of the drum 29 so that, when the lever 65 is moved to open the gripper 64, it also locks the drum 29 against movement until the grippers are again allowed to close.

In front of the drum there is mounted a moistening roller 73 which is supported from the side frames 10 and 11 and which has a gear 74 at one end (see Fig. 3) driven by a gear 75 which in turn is driven by the gear 32. The gear 75 is mounted upon a stud 76 carried by the side frame 10. The moistening roller 73 preferably is constructed of a suitable composition that is non-absorbent but which is readily wetted by the moistening liquid for the copy sheets. Beneath the roller 73, there is mounted an absorbent roller 77 which is carried on a pair of arms 78, only one of which is shown. The arms 78 are mounted on stub shafts 79 and are yieldingly forced upwardly to press the roller 77 against the roller 73 by means of a spring 80, one end of which engages one of a series of notches 81 provided in an extension of the arm 78. The other end of the spring 80 is secured to a pin 82 which is secured to the side frame 11 and projects inwardly therefrom.

A moistening liquid container 83 is mounted on a pair of supporting shafts 84 and 85 secured in the side frames 10 and 11 and has a wick 86 which engages the roller 73. Liquid is supplied to the container 83 for moistening the wick 86 from a reservoir 87 that is mounted in the front frame member 15. A pump 88 is provided in the reservoir 87 for pumping moistening liquid through a conduit 89 to the container 83. The pump 88 comprises a pump cylinder 90 and a piston 91 therein pressed downwardly by means of a spring 92. The piston 91 has a piston rod

93 which projects upwardly through the top of the cylinder 90 and is secured to a pump operating lever 94. The pump operating lever has a finger piece 95 thereon. The pump operating lever 94 is pivoted on a stud 96 carried by the side frame 11 and is limited in its downward movement by a stop arm 97 which is secured thereto in a suitable manner as by welding and which cooperates with the lever 94 to provide a slot 98 in which the piston rod 93 is received. The piston rod is provided with a nut 99 against which the lever 94 engages.

The lower end of the stop arm 97 is provided with a roller 100 which rides upon a cam 101 fixed on a shaft 102 which is journaled in the side frames 10 and 11. The cam 101 may be adjusted to limit the downward movement of the lever 94 and thus the downward stroke of the piston 93 by turning the shaft 102. A knurled knob 103 is fixed on the end of the shaft 102 outside the frame 11. An operating lever 104 for lifting the lever 94 is also pivoted upon the stud 96 and has a laterally extending lug 105 extending under the lever 94. The lever 104 is adapted to be engaged by a roller 106 which is carried by a cam lever 107 pivoted upon a stud 108 which is mounted on the side frame 11.

The shaft 60 has a sleeve 109 rotatably mounted thereon, and this sleeve has fixed thereto a pair of arms 110 and 111. The arm 110 also engages the roller 106 on the cam lever 107 so that, when the cam lever 107 moves in a counter-clockwise direction from the position shown in Fig. 1 to that shown in Fig. 2, the arm 110 is carried with it, and both arms 110 and 111 move together because of the sleeve 109. The cam lever 107 is actuated by means of a cam 112 which engages a roller 113 on the cam lever 107. The cam 112 is fixed to a gear 114 which is journaled upon a stub shaft 115 carried by the side frame 11. The cam 112 is spaced from the gear 114 by means of spacers 116 through which a series of rivets 117 pass to secure the cam and gear together.

The means for driving the gear 114 comprises a pinion 118 which is fixed upon a shaft 119 that is journaled in a bearing 120 provided on the plate 19. A hand lever 121 is fixed to the outer end of the shaft 119 so that it may be rotated.

The arms 110 and 111 cooperate to actuate a sheet feeding mechanism by which copy sheets may be fed to the rolls 73 and 77. The sheet feeding mechanism, as shown best in Figs. 1 to 4 and 7, comprises a copy sheet tray 122 mounted between the side frames 10 and 11 and having a lip 123 extending forwardly to a point adjacent the bight of the rollers 73 and 77. The copy sheet tray 122 has adjustable guides 124 and 125 thereon by which a block of sheets shown at 126 may be positioned on the tray. A back stop 127 is provided at the outer end of the tray 122. The sheets are advanced from the top of the stack 126 by a pair of friction rollers 128 and 129 that are carried in a frame 130. The frame 130 includes side flanges 131 and 132 notched as shown at 133 to receive a shaft 134 which carries the friction rollers 128 and 129. The frame 130 has a bar 135 adjustable longitudinally of a pair of slots 136 provided in the side flanges 131 and 132 to engage the friction rollers 128 and 129 when they are pressed back against it and prevent rotation of these rollers. The frame 130 has a hub 137 secured to a cross bar 138 by a set screw 139. The bar 135 is adjustably secured to the frame 130 by a screw 140.

which passes through an opening in the frame 130 and through a slot 141 in the bar 135. Referring now to Fig. 7, where it is best illustrated, it will be evident that, if the frame 130 is moved to the right by sliding it along the top of the pile of sheets 126, the friction rollers 128 and 129 will move back against the cross bar 135 due to their shaft being free to slide in the slots 133. When the friction rollers engage the cross bar 135, they will not rotate any further and will tend to slide the top sheet of the pile 126 to the right with them.

The cross bar 138 is carried by a pair of brackets 142 and 143. These brackets are fixed to side rods 144 and 145 which are slidably mounted in a bracket 146 on the side frame 10 and a bracket 147 on the side frame 11. In addition, the rods are slidably mounted by a second pair of brackets 148 and 149 which are riveted against the plates 18 and 19 and carry suitable bearings for the rods 144 and 145. The rods 144 and 145 are connected to the arms 111 and 110 respectively by a pair of links 150 and 151. The links 150 and 151 are pivoted to a pair of U-shaped members 152 and 153 that are riveted to the rods 144 and 145. The structure just described is such that, when the lever arms 110 and 111 are moved from the position shown in Fig. 1 to that shown in Fig. 2, they move the rods 144 and 145 with them thereby advancing the friction rollers 128 and 129 toward the rolls 73 and 77 and causing them to move the top sheet of the pile 126 into the bight of the rolls. In order to guide the top sheet to the bight of the rolls, a guide plate 154 is mounted over the lip 123 to provide a guide passage leading directly to the rolls.

In order to drive the drum through a complete rotation and to advance the copy sheets, to the rolls 73 and 77, while the rolls and drum are stationary, there is provided a drive mechanism between the pinion 118 and the gear 33 by which the drum is given a dwell or stationary period while the pinion 118 continues to drive the cam 112. This drive mechanism comprises a pinion 155 which is carried by a stub shaft 156 journaled in a suitable bearing 157 provided in the frame 11. The pinion 155 drives a gear 158 which is rotatably mounted on a stub shaft 159 fixed to the frame 11. The gear 158 has riveted thereto a mutilated gear 160, the form of which is shown best in Fig. 6. This mutilated gear is adapted to mesh with the gear 33 to rotate the gear 33 for a complete rotation, and then continue to rotate while the gear 33 remains stationary for the amount necessary to move a smooth portion 161 of the gear 160 past the gear 33. This smooth portion 161 constitutes about one-fourth of the gear 160 and the gear ratio between the pinion 155, and the gear 158 is such as to require four rotations of the pinion 155 for one rotation of the gear 158.

The driving relation between the gear 158 and the gear 114 which drives the cam 112 is such that, during the period of rotation of the gear 158 that moves the smooth portion 161 of the gear 160 past the gear 33, the gear 114 turns the cam 112 to cause it to move the lever 107 from the position shown in Fig. 1 to the position shown in Fig. 2 and to hold it there until the gear 33 has been again started in rotation. The cam 112 then releases the lever 107 and the sheet feed actuating mechanism comprising the arms 110 and 111, the rods 144 and 145 and the 75 parts carried thereby to be returned to starting

position. This return is accomplished by a return spring 162 (see Fig. 1) which extends between the pin 82 and the arm 110 and is under sufficient tension to retract the sheet feeding mechanism.

While certain embodiments of the invention have been shown and described, it is to be understood that it is capable of many modifications. Changes, therefore, in the construction and arrangement may be made without departing from the spirit and scope of the invention as disclosed in the appended claims in which it is the intention to claim all novelty inherent in the invention as broadly as possible in view of the prior art.

Having thus described the invention, what I claim as new and desire to secure by Letters Patent is:

1. In a duplicating machine of the character described, a frame, a drum rotatably journaled therein, means to mount a master sheet on said drum, drive means for said drum including means operable automatically to cause successive revolutions of the drum with dwell periods between the revolutions upon continued operation of said drive means, a plurality of cooperating moistening and feeding rolls driven by said drum for moistening copy sheets fed thereto, and sheet feeding means, actuated by said drive means during the dwell period of said drum, to advance copy sheets into position for laying on said master sheet when the drum is again rotated, means for supplying moistening liquid to one of said rolls including a pump, said drive means including a cam, and a cam lever operatively connected to the sheet feeding means and the pump to actuate both of them.

2. In a duplicating machine of the character described, the combination of a rotatable drum, means comprising a driving member adapted by continuous actuation to give said drum a rotary movement and then to hold the drum stationary for a short period, means for forwarding copy sheets past said drum, a table for holding copy sheets in position to be fed therewith to said forwarding means, bars slidably mounted at opposite sides of said table, sheet feeding means operatively connected with said bars so as to be movable thereby along the table toward and from said drum upon reciprocatory movement of the bars for feeding copy sheets one at a time to said forwarding means, means connecting said bars together for causing them to move in unison, and means for giving said bars an operative stroke for feeding a copy sheet toward the drum at each period when said drum is standing stationary, said means comprising two oppositely extending pivotally mounted members positioned at different levels so as to overlap at their end portions, the upwardly extending member being operatively connected with said bars for reciprocating them and the downwardly extending member being in engagement with said upwardly extending member for actuating it.

3. In a duplicating machine of the character described, the combination of a rotatable drum, means comprising a driving member adapted by continuous actuation to give said drum a rotary movement and then to hold the drum stationary for a short period, means for forwarding copy sheets past said drum, a table for holding copy sheets in position to be fed therewith to said forwarding means, sheet feeding means movable along the table toward and from said drum for feeding copy sheets one at a time to said for- 75

- warding means, a rock shaft extending across below the drum, two arms rigidly mounted at their lower ends on said rock shaft and connected at their upper ends with said sheet feeding means, a spring urging said arms in the direction for movement of the sheet feeding means away from the drum, and means for swinging said arms in the direction for carrying the sheet feeding means toward the drum at each period 5
- 10 when said drum is standing stationary, said arm swinging means comprising a downwardly extending pivotally mounted member engaging one of said arms for swinging it and means for giving said downwardly extending member an operative swinging movement in timed relation to the rotation of said drum.
- 15 4. In a duplicating machine of the character described, the combination of a rotatable drum, means comprising a driving member adapted by continuous actuation to give said drum a rotary 20 movement and then to hold the drum stationary for a short period, means for forwarding copy sheets past said drum, a table for holding copy sheets in position to be fed therealong to said 25 forwarding means, sheet feeding means movable along the table toward and from said drum for feeding copy sheets one at a time to said forwarding means, a rock shaft extending across below the drum, two arms rigidly mounted at 30 their lower ends on said rock shaft and connected at their upper ends with said sheet feeding means, a spring urging said arms in the direction for movement of the sheet feeding means away from the drum, a cam, means for giving 35 said cam a complete revolution for each complete cycle of movement of said driving means, and means actuated by said cam for swinging

said arms in the direction for carrying the sheet feeding means toward the drum at each period when said drum is standing stationary, said arm swinging means comprising a pivotally mounted member extending past said cam in position to be actuated thereby and adapted to engage one of said arms so as to swing it in timed relation to the rotation of said drum. 5

5. In a duplicating machine of the character described, the combination of a rotatable drum, 10 means comprising a driving member adapted by continuous actuation to give said drum a rotary movement and then to hold the drum stationary for a short period, means for forwarding copy sheets past said drum, a table for holding copy 15 sheets in position to be fed therealong to said forwarding means, sheet feeding means movable along the table toward and from said drum for feeding copy sheets one at a time to said forwarding means, a rock shaft extending across 20 below the drum, two arms rigidly mounted at their lower ends on said rock shaft and connected at their upper ends with said sheet feeding means, a spring urging said arms in the direction for movement of the sheet feeding means 25 away from the drum, a lever pivotally mounted on a horizontal axis above one of said arms and adapted upon an operative stroke to engage said arm and move it in the direction for carrying the sheet feeding means toward the drum, a cam 30 adapted by engagement with said lever to give it an operative stroke upon each complete revolution of the drum, and means for rotating said cam in such timed relation as to move said sheet feeding means toward the drum at each period 35 when the drum is standing stationary. 35

ALFRED MARCHEV.
